BOX

Michael M. Brodsky, Brooklyn, N. Y., assignor, by
mesne assignments, to Johnson & Johnson, a
corporation of New Jersey

Application January 21, 1933, Serial No. 652,788

4 Claims. (Cl. 229—17)

This invention relates to an improvement in boxes or cartons, and particularly to a type of box adapted for containing a number of small packages or envelopes arranged for successive removal from the box.

One of the objects of the invention is to provide a box of this character, inexpensively constructed, so that it may be furnished to a customer as a protective carton or container for its contents, which are in the form of relatively flat packages or envelopes and which are adapted to be drawn out one at a time from a slot in the box until they are depleted, the articles in the box being gravity-fed toward the outlet opening so that as one is removed, the next article presents itself in position for removal.

More particularly, the invention contemplates a cardboard receptacle having sealed ends formed by overlapping flaps on the blank from which the box is made, one of the panels of the box being provided with a discharge opening located at its extreme lower end, said opening being formed after the box is acquired by the purchaser, by tearing out a part of the body of the box that is defined by weakened tear lines produced during the manufacture of the box. The discharge opening or slot so formed may be of relatively narrow width and is provided with one or more widened portions constituting finger-entrance openings, one of which is located in the bottom of the box so that the lowermost package or envelope in the box is readily accessible to the fingers and may be easily engaged and withdrawn from the box.

In the accompanying drawing, wherein several embodiments of the invention are shown, Fig. 1 is a plan view of the blank from which one form of the improved box is made; Fig. 2 is a perspective view of a box made from the blank shown in Fig. 1, showing the same as it appears after it has been emptied of its contents; Fig. 3 is a vertical sectional view of the box, with the contents partly removed from it; Fig. 4 is a transverse sectional view through the box, the view being taken through the part of the box where the discharge opening is located; Fig. 5 is a vertical sectional view through the part of the box where the discharge opening is located, before the discharge opening has been produced by tearing out the removable part of the box body.

In Fig. 1 of the drawing, the blank is disclosed from which the box shown in Figs. 2 to 5 is formed. It comprises a cardboard sheet divided by fold lines to form it into a front panel 10, side panels 11 and 12, a back panel 13, a secur-

ing flap 14, top flaps 15 to 18 and bottom flaps 19 to 22. When the blank is folded on the dot-and-dash lines shown in Fig. 1, it assumes the shape shown in Figs. 2 and 3. To maintain it in that shape, the securing flap 14 is adhesively attached to the side wall 12 and the bottom flaps 19, 20, 21 and 22 are also adhesively secured together in the conventional way in overlapping relationship to close the bottom of the box. Likewise, after the box is filled, such as with relatively flat packages or envelopes 23 or other contents, the top flaps 15 to 18 inclusive are adhesively secured together in overlapped relationship to seal the box and protect its contents.

At 24 is indicated a removable panel provided in the front 10 of the box, the panel being defined by a weakened tear-line 30 that it may be easily removed to provide the discharge opening or slot 25 through which the lowermost article in the stack within the box is reached by the fingers 26 and 27 and withdrawn through the discharge opening. This operation is facilitated by the finger entrances 26 and 27 constituting widened portions of the discharge opening 25. The finger entrance 26 is located in the front panel of the box, while that shown at 27 is formed in the bottom of the box and extends through the several overlapping bottom flaps 19 to 22 inclusive. Through this arrangement the relatively flat packages or envelopes 23 may be gripped flatwise between the fingers and drawn out of the box without being crushed. To enable the finger entrance 27 to extend through the several bottom flaps, one of the edges on each of the flaps 19, 20 and 22 is recessed at 28 during the manufacture of the box blank, these recesses lying in registration with one another when the box is assembled and in registration with the part 29 of the tear-cut panel 24.

When the purchaser obtains the box, it is completely sealed. By tearing out the panel 24, he may easily insert his fingers through the finger entrances 26 and 27 and grasp the lowermost envelope or package 23 in the box, drawing it out through the discharge opening 25 as clearly indicated in Fig. 3. When the lowermost article is withdrawn, that which is located above it drops down in position to be removed, this continuing until the contents of the box are depleted. The box, being of simple one-piece construction, can be supplied without additional cost in place of those ordinarily used, with the added feature of easy dispensation of the contents, provided.

What I claim is:—

1. A box or carton provided with a front wall

and overlapping bottom closure flaps, several of the closure flaps being provided with recesses in their edges, the recesses being located in alignment when the flaps are in overlapped relationship, a tear-out panel formed in the front of the box, said panel when removed producing a discharge slot, said tear-out panel being connected with a tear-out portion of one of the bottom flaps, said portion when removed with the tear-out panel forming a recess in the flap of which it was a part, which recess lies in alignment with the recesses in the other bottom flaps so that the several aligned recesses cooperate to form a finger opening through the several bottom flaps, the front wall of the box also having a finger opening formed by the removal of the tear-out panel.

2. A box or carton having a front panel, a bottom composed of several overlapping, united flaps, some of said flaps having aligned recesses at the front of the box, one of said flaps being an imperforate flap, a tear-out panel in the front of the box being connected with a portion made up of a part of the imperforate flap and so shaped that when it and said portions are removed it will form a recess in the imperforate flap in alignment with the recesses in the other flaps without disturbing the relationship of the imperforate flap to the other flaps.

3. A box or carton having a front panel, a bottom composed of several overlapping united flaps, some of said flaps having recesses in their edges located in alignment when the flaps are in their overlapped relationship, one of the flaps being an imperforate flap, a tear-out panel in the front of the box producing a discharge slot when

removed, said panel being connected with a portion made up of a tear-out part of the imperforate flap, which part lies in registration with the aligned recesses in several of the united flaps so that when the tear-out panel and said portion are removed a recess corresponding to and in alignment with the recesses in the several united flaps will be produced in the imperforate flap without disturbing the relationship of said flap to the other flaps, a portion of the tear-out panel serving to form a finger opening in the front panel when the tear-out panel is removed. 5 10

4. A box or carton provided with a front wall and overlapping bottom closure flaps, said bottom flaps being all of substantially the same 15 size, several of said closure flaps being provided with recesses in one of their edges, the recesses being located in alignment when the flaps are in overlapped relationship, a tear-out panel formed in the front of the box, said panel when 20 removed producing a discharge slot, said tear-out panel being connected with a tear-out portion of one of the bottom flaps, said portion when removed with the tear-out panel, forming a recess in the flap of which it was a part, which 25 recess lies in alignment with the recesses in the other bottom flaps so that the several aligned recesses co-operate to form a finger opening extending through the several similarly-sized bottom flaps, the front wall of the box also having 30 a finger opening formed by the removal of the tear-out panel, the several similarly sized bottom flaps forming a multi-layered bottom of uniform thickness for the box on which the contents thereof are supported. 35
